Primary Examiner—Ruth McInroy
Attorney, Agent, or Firm—Brooks & KushmanP.C.[57] **CLAIM**

The ornamental design for a stove burner, as shown.

DESCRIPTION

FIG. 1 is a top plan view of a stove burner showing my new design;

FIG. 2 is a front elevational view of FIG. 1;

FIG. 3 is a left side elevational view of FIG. 1;

FIG. 4 is a right side elevational view of FIG. 1;

FIG. 5 is a rear elevational view of FIG. 1;

FIG. 6 is a bottom plan view of FIG. 1;

FIG. 7 is a top plan view of a second embodiment thereof;

FIG. 8 is a front elevational view of FIG. 7;

FIG. 9 is a left side elevational view of FIG. 7;

FIG. 10 is a bottom plan view of FIG. 7;

FIG. 11 is a top plan view of a third embodiment thereof;

FIG. 12 is a front elevational view of FIG. 11;

FIG. 13 is a side elevational view of FIG. 11; and,

FIG. 14 is a bottom plan view of FIG. 11.
